FIG. 1 is a perspective view of the multi-lobed abutment of the present invention.

FIG. 2 is a top plan view thereof;

FIG. 3 is a left side elevational view thereof; the right side elevation view being mirror image thereof;

FIG. 4 is a front elevational view thereof;

FIG. 5 is a bottom plan view thereof; and,

FIG. 6 is a rear elevational view thereof.

Phantom lining where utilized, is for illustrative purposes only and is not intended to limit the claimed design to the features shown in phantom.
